UNITED STATES PATENT OFFICE.

FRANK ZALESKI, OF CAMBRIDGE, AND AUGUST R. SCHOENKY, OF SOMERVILLE, MASSACHUSETTS, ASSIGNORS TO REECE SHOE MACHINERY COMPANY, OF BOSTON, MASSACHUSETTS, A CORPORATION OF MAINE.

MACHINE FOR STITCHING SHOE-UPPERS TO SOLE-LIPS.

1,288,366.

Specification of Letters Patent.

Patented Dec. 17, 1918.

Application filed January 9, 1915. Serial No. 1,282.

To all whom it may concern:

Be it known that we, FRANK ZALESKI and AUGUST R. SCHOENKY, respectively subject of the German Emperor and citizen of the 5 United States, residing at Cambridge and at Somerville, respectively, in the county of Middlesex and State of Massachusetts, have invented certain new and useful Improvements in Machines for Stitching Shoe-Uppers to Sole-Lips, of which the following 10 is a specification, reference being had therein to the accompanying drawing.

This invention is an improved machine 15 for stitching shoe upper to sole lip; this being a very special class of machine employed for producing a chain stitch, by the aid of a hooked, curved needle, and coöperating movable stitching instruments, namely, thread looper, take-up, and work feed device, and 20 usually also, thread hook, channel guide, welt feed device, and locking means for the latter, and for the yielding work support. Such machines are usually designed to serve 25 for either of two purposes, firstly, to stitch the upper and a strip of welt to the downwardly projecting lip of the insole of a welt shoe, or, secondly, to stitch the reversed upper to the upstanding lip of the sole of a turn shoe; whence this class of machine is 30 generally known as a "welt and turn" stitching machine.

The main object of the present improvement is to afford sewing machines of the kinds to which the invention is applicable, 35 having a more effective and durable construction than heretofore known machines and capable of a higher rate of speed. Another object, especially in shoe sewing machines, is to afford a lighter and therefore 40 faster running machine by dispensing with the ordinary construction of heavy rotating cams and using instead mechanism composed of comparatively light mechanical parts capable of high rapidity of action.

45 Another object is to afford harmonic actuation for such sewing machines, thus giving smoothness and ease of motion of the needle, looper, take-up, feed device and other stitching instruments, which may be over 50 five or six or seven in number, some having rapid oscillating and changing motions. Another object is to afford such a machine having an actuating mechanism substan-

tially free from the qualities of unbalance and fly-wheel effect involved in the old cam driven machines, and without the excessive noise and vibration thereof, and therefore capable of largely increased speed and output, with actually reduced strain on the workman, and without sacrificing the benefits of the appropriate cycle of stitching movements. Another object, conducing to the same results, is compactness by condensation and elimination of mechanism, so that relatively few connecting parts may drive 65 all the stitching instruments, and be accommodated in a small space behind the stitching point, at which the various actions converge, so leaving the workman free to do his part in manipulating the work. Another 70 object is to render less expensive as well as more durable such machines not only by the great reduction in machine parts, but in their simplicity of form and ease of manufacture and assembling.

To the attainment of the above objects, the present invention consists in the novel devices, arrangements, combinations, mechanical movements and other features described in the following specification or 80 illustrated in the accompanying drawings.

Particularly, the preferred plan of this improvement is in an actuating mechanism which commences with an operating crank shaft having several, for example four, pitmen driven by it, for actuation of a substantially larger number, (e. g., seven) stitching instruments, and from such smaller number of pitmen operating a system of rocking levers and links, arranged and extending 90 generally in planes perpendicular to the shaft, and transversely juxtaposed for compactness, to actuate the greater number of instruments, in the harmonic manner mentioned, and to secure the appropriate cycle of 95 motions.

We will first refer to the active instruments which perform the various operations on the shoe, and then describe a suitable mode of coöperative action therefor by a diagram, and will then describe a weltng machine embodying the present improvements and possessing the operation illustrated in such diagram.

In the accompanying drawings forming 105 a part hereof, Figure 1 is a diagrammatic

representation of the preferred operation of a welting machine embodying the present invention, although obviously the invention could be applied to machines having other 5 and different modes of operation.

Fig. 2 is a plan view of a welting machine embodying the present improvements.

Fig. 3 is a partial front elevation partly in section, on the plane 3—3 of Fig. 7.

10 Fig. 4 is likewise a part plan viewed partly in section, taken on the plane 4—4 of Fig. 7.

Fig. 5 is a left elevation partly in section, on the plane 5—5 of Fig. 2.

15 Fig. 6 is a section on the plane 6—6 of Fig. 7.

Fig. 7 is a left elevation of the entire machine, excepting that the supporting post is broken off and the base portion, controlling 20 pedals, etc., are omitted.

Fig. 8 is a partial left elevation showing some of the active instruments at or near the sewing point.

Fig. 9 is a front view of the parts shown 25 in Fig. 8.

Fig. 10 is a horizontal section on the plane 10—10 of Fig. 11.

Fig. 11 is a right-hand elevation of some 30 of the parts seen in Fig. 9.

Fig. 12 is a left elevation showing the connections which actuate the work support dog lock A'.

Fig. 13 is a plan of certain parts in 35 Fig. 12.

Fig. 14 is a left elevation showing the connections which actuate the channel guide B.

Fig. 15 is a left elevation showing the connections which actuate the needle C.

Fig. 16 is a left elevation showing the connections which actuate the looper D.

Fig. 17 is a left elevation showing the connections which actuate the thread hook E.

Fig. 18 is a left elevation showing the connections which actuate the take-up F.

40 Figs. 19 and 21 are left elevations showing the connections which actuate the feed point G, while Fig. 20 is a plan view of certain parts thereof.

Fig. 22 is a left elevation showing the connections which actuate the welt feed and 45 guide H.

For convenience, the active instruments which perform operations upon or coöperate with the work will be designated by a system of reference letters, while the mechanical connections for causing the instruments to perform their respective functions at the proper point in the cycle of operation will be 50 designated by numerals.

60 It will be understood that the operator holds the inverted shoe in stitching position and performs any necessary turning or guiding as the feed operates and stitching progresses.

65 A work support A having a sliding shank

a presents an upright front surface against which the upper of the shoe bears during the stitching. A spring a³ tends to hold the work support forward. The work support has to be locked and released at certain 70 points in the cycle of operations, and a locking dog device A' having a swinging shank a' is utilized for the purpose. Incidentally, the locking dog A' serves when operative to lock in forward position not only the work 75 support A but the welt guide and feed member H hereinafter to be referred to, so that the instruments A and H serve effectually to oppose the force of the feed point G hereinafter mentioned, when the latter strikes 80 the work.

A guide B having a shank b is so positioned above the work that the extremity of the guide enters the channel which has been previously formed around the outer margin 85 of the insole of the shoe, thus giving additional guidance to the shoe and insuring the proper positioning of the stitches. It will be understood that the channel of the insole forms a lip which is turned out by the channel guide and which lip is stitched to the shoe upper and the welt thereby connecting the three, preparatory to the subsequent attachment of an outsole to the welt. The channel guide is required to be moved 90 slightly during every cycle of operations.

An oscillating curved needle C is carried upon a block c in a general forward and rearward direction, the needle penetrating first the welt, then the upper and then the 100 insole, and returning during each stitch, the thread being suitably manipulated to produce a continuous line of chain stitching.

A thread looper D carried at the lower end of an upright screw-threaded spindle d oscillates about one and one-eighth revolutions for manipulating the thread in the formation of each stitch. The spindle is engaged by a vertically sliding nut d' which turns it.

Coöoperating with the looper is a thread hook E at the forward end of a carrying shank or arm e.

Also coöoperating with the looper and thread hook is a take-up F located at the forward end of its carrying arm or shank f. 110 Associated with the take-up F is a resilient or auxiliary take-up F'.

A feed point G formed with an upwardly extending shank or carrying arm g is located to engage with the lip of the shoe insole 120 and in fact is caused to pass through an aperture provided in the channel guide B for that purpose; the feed point having a movement to and from the work for engaging and disengaging, and a movement longitudinally of the work for feeding the work between stitches.

In addition to the above parts A to G is a member H which performs the services both 130 of a welt guide and a welt feeder, it being

carried on its sliding shank *h* and having a certain movement during each cycle for feeding the strip of leather or welt to the stitching point in harmony with the advance of the shoe during the stitching operation.

- The diagram Fig. 1 need not be explained in detail as it is suitably labeled and is therefore self-explanatory. The length of the diagram horizontally indicates one cycle of operations of the various instruments A' to H, and it will be understood that such cycle will be repeated stitch after stitch. The reference A' for the work support locking dog, and the references B, C, D, E, F, G, H, for the channel guide, needle, thread looper, thread hook, take-up, feed point, and combined welt guide and feed respectively, have been applied to the eight curves or lines of the diagram.
- 20 The nature of the curves in the Fig. 1 diagram shows that the action or motion of all of the instruments is what may be termed harmonic; there is no such jerk or thrust as is involved in cam operated connections, the motion of each instrument, on the contrary being analogous to that of a steam engine cross head which changes speed and direction without suggestion of shock.

At the top of the post of the machine is 30 the head 50 carrying the various mechanical parts hereinafter to be described. It will be understood that any convenient shaft driving and stopping means can be employed, and any convenient pedals, control levers, 35 and the like. The disclosure herein is directed more particularly to the mechanisms for securing through stitch after stitch the proper cycle of operations for each of the active instruments A to H of the machine.

- 40 In the upper part of the head, suitably supported in a bearing standard 51 and one of the two vertical walls or plates 52—52, is the main shaft 53 of the machine, from which in the present embodiment all of the 45 operations to be described are effected.

The shaft 53 is a crank shaft having two cranks or pins which actuate four crank rods. The first or left-hand crank 56 is between the standard 51 and the left-hand 50 wall 52 of the head, while the second or right-hand crank is inside or between the walls 52.

- The outside crank 56 operates through a first crank rod 61, while the inside crank 57 55 operates through a second crank rod 63 and a third crank rod 65 and a fourth crank rod 64; the four crank rods being arranged from left to right in the order mentioned.

The actuation of all of the instruments 60 A' to H is effected from the four crank rods by the intermediate mechanism next to be described.

The free end of the crank rod 63 is guided in its to-and-fro movements by a swingable arm 71, and from the pivot of the rod and

arm extends a link 72 to a large and important oscillating lever 73. This lever 73 effects or influences the operation of the work support locking dog A', the needle C, the thread hook E, the feed point G, and the 70 welt guide and feed H. The parts 63, 71, 72, 73 are seen in Fig. 12.

The further connecting mechanism will now be described by considering in turn each of the instruments A' to H and showing the actuating connections to it from the mechanisms already described.

The shank *a'* of the locking dog A' which locks in their forward position both the work support A and the welt feed and 80 guide H, is horizontally swingable for applying its two dogs to the two members, to lock and unlock them. The actuation is effected by means of an arm 74 downwardly extending from the lever 73 and having a 85 roller at its extremity which strikes a sharp blow upon the slanted rear end of the shank *a'*, to unlock the dogs, against the resistance of a leaf spring *a*² which tends to force the dogs into locking position. See Figs. 12 90 and 13.

The channel guide B is actuated from a rock shaft 76 which in turn is actuated by the crank rod 61 through a link 62 which is directly pivoted to the arm 75 of the rock 95 shaft 76, the rock shaft having a second or downward arm 77 which through a link 78 causes the reciprocation of a slide 79 which in turn connects with the swinging shank *b* of the channel guide. The shank for convenience swings loosely on the feed point shaft 101. See Fig. 14. The shank *b* surrounds the shaft 101 between the same collars 102 which include the feed point hub, so that, when the shaft moves axially to 105 operate the feed point, the channel guide is caused to move along with the shaft and feed point. This relative movement is permitted by the illustrated sliding connection between the upper forward end of the slide 110 79 and the upward extremity of the channel guide shank *b*, the latter having a rightwardly projecting stud 84, (see Figs. 2 and 3), which is pressed by spring 85 into contact with the concave end of the slide. 115

The needle C carried on the block *c* is operated directly from the large lever 73 through a floating link 80 directly connecting the extremity of the lever with the needle block. See Fig. 15. 120

The thread looper D is caused to swing around with its screw spindle *d* by a vertical sliding nut *d'* engaging the screw spindle, the nut being actuated from the crank rod 61 by the following connections. The free 125 end of the crank rod is guided in its movements by a swinging arm 81. The arm 81 is fulcrumed at one end and at an intermediate point has connected to it another link 82 extending to an intermediate point on an- 130

other lever 83 which swings about one end and at the other end is connected by a link 86 directly to the sliding nut d' for causing the up-and-down movements of the latter.

5 See Fig. 16.

The thread hook E is actuated jointly from the lever 81 already mentioned (actuated from the crank rod 61) and from the large lever 73 as follows: An upwardly extending arm 87, rigid with the large lever 73, is connected by a link 88 with another link 89, the latter pivoted to the middle part of the lever 81. Thereby the movements of the two levers control the position 10 of the juncture or pivot between the two links 88 and 89, and from this pivot extends a third link 90 to the extremity of the swinging shank e of the thread hook. See Fig. 17.

The take-up F at the extremity of its 20 swinging shank f is actuated from the crank rod 64 as follows. The crank rod is guided in its movements by a swinging arm 91, the extremities of the rod and arm being connected to each other and to a link 92 which 25 extends to the swinging shank or lever f. The arm 91 for convenience swings loosely about the rock shaft 76. See Fig. 18. The auxiliary take-up F' and its connections are shown more particularly in Figs. 6 and 30 7 and will be separately explained hereinbelow.

The feed point G has both rearward and forward movement for engaging and disengaging the work, and right and left movement for feeding. The forward and backward movement is effected from the large lever 73. The feed movement is effected from the rock shaft 76 rocked by the crank rod 62. The connections may be as follows. 35 See Figs. 19, 20, 21. A link 93 extends from the upward arm 87 of the large lever 73 to one arm of a bell crank 94 whose other arm is connected by a link 95 to the swinging shank or arm g of the feed point, which fulcrums about its carrying shaft 101. Thus 40 the feed point is swung in and out. The rock shaft 76 has a downward arm 96, which in its rocking movements actuates a link 97, which extends to a feed slide 98, which by 45 a link 99 actuates a bell crank 100, which longitudinally slides a slide rod or shaft 101, which carries two collars 102—102 between which is the hub of the feed point and also the hub of the channel guide shank b. Thereby 50 the feed point can be swung about the shaft 101 for engaging and disengaging the work, and can be shifted rightward and leftward with the shaft 101 for feeding purposes. As the shaft shifts leftward and rightward 55 carrying the channel guide and feed point with it, the former is permitted to partake of the sliding movement by the sliding connection 84 already described; and the feed point similarly is permitted to partake of 60 the movement by a sliding connection be-

tween its shank g and the link 95 which swings it. Thus, as seen in Fig. 2, the link has a rightwardly projecting stud 111, upon which the shank g engages and slides.

The welt member H which both guides 70 and feeds the welt and is carried upon the sliding shank h, is actuated from the large lever 73 and from the crank rod 65 as follows: A link 103, pivoted to the lever 73 at one end, is connected at the other end to the 75 extremity of the crank rod 65, and at the juncture of the link and rod is pivoted another link 104 which extends to one arm of a bell crank 105 whose other arm is connected by a link 106 to a swinging arm 107 pivoted 80 at 109. A second arm 108 is also pivoted at 109, and its extremity connects directly with link 110 which moves the sliding shank h of the welt member. The relation between the two arms 107 and 108 is such that the 85 arm 107 may swing the arm 108 backward only to retract the welt member H, while a spring h' is relied upon to force the same forwardly, and the locking dog A' is relied upon to hold it forward for a suitable time. 90 See Figs. 22 and 12.

The auxiliary take-up F' is a passive device of a resilient nature. This is a well-known instrument and may be similar to the member b⁵ of Fig. 7 of expired U. S. Patent No. 412,704. The device F' comprises a thread wheel at the end of a swinging arm f' mounted on the same fulcrum with the take-up. The thread wheel of the main take-up F is slightly offset, as seen in plan view 100 Fig. 2, so that the thread wheel F' is arranged in the same plane with the other and below and to the rear thereof. The auxiliary take-up arm f' has a rear extension 113 beyond its fulcrum, and this is connected by a link 114 with a swinging lever 115 fulcrumed at its top end, see Figs. 7 and 6. A spring 116 tends to move lever 115 forward and thereby lower the auxiliary take-up. 10.

The purpose of the device is to maintain the thread taut at all times so as to avoid slack, being capable, however, of yielding when the stitch is set. To avoid an abrupt stoppage in yielding under the pressure of the thread and the consequent rebound the auxiliary take-up is cushioned although positively stopped. When the main take-up F operates to set the stitch its rising movement lifts the auxiliary take-up because of the tension on the thread. This operates through link 114 to press lever 115 rearward until the lever comes to a positive stop against the device shown in Fig. 6, which includes a spring-pressed buffer 117 capable of yielding until lever 115 comes in contact with the frame part 52. The buffer has a stem with a head 118 by which its normal forward position is predetermined. 115

We have not attempted in the above description of the parts to point out com- 120 125 130

- pletely the relation between the various links, levers, etc. To so describe them would require great length of description, whereas the disclosure in the drawings speaks for it.
- 5 self and the explanatory diagram, Fig. 1, sufficiently shows the operation or the result of the actions of the mechanical connections when put through their motions by the rotation of the main shaft 53.
- 10 The shaft, looking at the machine from the left end, rotates counter-clockwise, and the outside crank 56 is timed sixty degrees behind the inside crank 57. The various crank rods extend in different directions from the 15 several cranks, and this arrangement in conjunction with the form, position, size and arrangement of the parts numbered 71 to 110 secures the precise movements desired for the various active instruments A to H of the 20 machine.
- The following, among other adjustments, may be made on the described machine. The welt feed may be adjusted by the set screw 120 interposed between the arms 107 and 108, 25 Fig. 22. The feed of the work or the amount of reciprocation of the feed slide and point may be adjusted by shifting the pivot of link 97 along the slot 121 of arm 96, Fig. 21. The welt guide position is adjustable by the set 30 screw 122, Fig. 22. The channel guide may be adjusted to different operative positions and out of operative position, for example, by the stop screw 123 carried by the shank b, Fig. 14. Other analogous adjustments are 35 capable of being introduced into the described machine.
- The hereinabove description is supplementally explained as follows: The continuously rotating shaft 53 operates a plurality 40 of cranks, namely, its two cranks 56 and 57, which are differently timed. These cranks actuate the various mechanical connections to the needle and other instruments of the machine through a plurality of pitmen. 45 Thus pitman 61 is on crank 56, while crank 57 drives a plurality of pitmen, namely, 63, 64 and 65 which, while mounted on the same crank, are differently timed because extending in different directions.
- 50 The various trains of connections to each of the instruments A, B, C, D, E, F, G, H, all commence with the shaft 53 and, in fact, with one or the other of the cranks 56 or 57 and, in fact, with one or another of the pitmen 61, 63, 64, 65. The actual link and lever connections between the pitmen and the instruments has been described and the action will be understood from the drawings. Among the mechanical parts may be mentioned three rockers or rock levers, each of 55 which takes part in the actuation of two or more of the instruments. The first rocker 70 comprises the arms 73, 74 and 87 and the hub with which they are all rigidly formed. The 60 second rocker 76 comprises the arms 75, 77 and 96 and the rock shaft with which they are rigidly formed. The rockers 70 and 76 are co-axially arranged, and the hub of rocker 70 loosely surrounds the shaft of rocker 76, this shaft constituting a sort of 70 axle arranged parallel to the operating shaft 53 near the extreme rear of the machine. The third rocker is the lever 81 which actuates the links 62, 82 and 89.
- While the several instruments, particularly the needle, feed device, channel guide, thread looper, take-up and welt feeding guide, coöperate generally in a well-known manner to produce successive stitches, it will be observed that the to and fro movements of each instrument are of a harmonic nature, being, as before explained, free from the jolting action of cams. The harmonic motion is indicated in the Fig. 1 diagram in which it will be seen that each instrument 85 passes through its cycle of action in the smoothest possible manner without sudden changes of motion. According to this invention these motions are attained as to the greater number or all of the instruments by 90 trains of mechanisms consisting wholly of pitmen, links and levers, crank-actuated from the operating shaft.
- The coöperative action of the several instruments secured by the crank, link and 95 lever mechanisms mentioned may be substantially as follows.
- The needle C is a hooked, curved needle adapted, fitted and operated to penetrate the work, to then receive a loop of the single 100 thread, to then return through the work with the thread loop and to occupy such thread loop on the succeeding penetrating stroke; this cycle being repeated indefinitely to produce chain stitches.
- The thread looper D is movably fitted and operated so as to place a thread loop upon the hook of the needle on each penetrating stroke of the needle.
- The take-up F is movably fitted and operated so as to take-up the slack thread during each penetrating stroke of the needle and to give thread on the return stroke.
- The work feed device or feed point G is movably fitted to engage with the work and 110 to advance the work while the needle is out of the work and to thereafter disengage the work and return for a repetition of feed movement. It thus has an advancing and receding movement along the direction of feed and a reciprocating movement toward and from the work.
- The channel guide B is movably fitted to advance and recede in conjunction with the feed device and also to reciprocate to and 125 from the work.
- The movement of the feed device and channel guide along the direction of the work feed, which is substantially parallel to the crank shaft 53, is at right angles to 130

the planes of movement of substantially all of the other connections. The slide rod or shaft 101 is shown parallel to the operating shaft, and the bell crank 100 constitutes a contrivance which is adapted, when one arm is moved in a plane at right angles to the shaft, to produce motion in the other arm, and in the slide rod, feed device and channel guide, parallel to the shaft. The connections for producing the other movements in the feed device and channel guide are shown as swinging wholly in the planes at right angles to the shaft.

10 The thread hook E is movably fitted and operated so as to take the thread between the looper and the work so as to assist the engagement of the needle and thread, the hook operating to release the thread after the loop is safely on the needle, that is, until 15 the needle is substantially withdrawn.

20 The welt feeding guide H is movably fitted and operated to measure a predetermined length of leather strip which is to constitute the welt, this being done while the needle is engaged in the work, and this 25 instrument subsequently laying the welt against the work during the feed.

30 The work support A intermittently becomes movable in alternation with the action of locking it forward. When locked the work support holds the work firmly to the channel guide during the retraction of the needle.

35 It will thus be seen that we have described one kind of sewing machine, namely, a shoe welt sewing machine operating according to the principles and attaining the objects and advantages hereinbefore referred to, and other advantages will be apparent to those 40 skilled in the art. Since many matters of design, arrangement, form, combination, details and other features may be variously modified without departing from the principles involved, no limitation to such features is intended excepting in so far as referred to in the appended claims.

45 What is claimed is:

1. A chain-stitch welt sewing machine for attaching together shoe upper and sole lip, 50 the same having at least five movable stitching instruments inclusive of the hooked needle, thread looper, take-up, channel guide, and feed devices for the work and welt, each mounted for its coöperative movement in relation to the others, and a harmonic actuating mechanism for said stitching instruments, comprising an operating crank shaft continuously rotatable during stitching, a plurality of pitmen substantially fewer than the stitching instruments and crank driven by said crank shaft, and connections from such smaller number of pitmen to the larger number of stitching instruments, including rocking levers and 55 links moving in planes perpendicular to the

shaft, at least one of said stitching instruments being actuated from a plurality of said pitmen, and at least one of said rocking levers taking part in actuating a plurality of said instruments, said connections 70 adapted to transmit motion to the stitching instruments to operate the same smoothly in proper timing to produce successive stitches.

2. A wax-thread shoe sewing machine for attaching together shoe upper and sole lip, 75 the same having at least six movable stitching instruments inclusive of the curved needle, thread looper, take-up, and feed device, each mounted for its cooperative movement in relation to the others, and a harmonic actuating mechanism for said stitching instruments, comprising a single crank shaft having less than four cranks for operating such six instruments, said shaft continuously rotatable during stitching, a plurality 80 of pitmen, crank - driven by said crank shaft, and fewer in number than such six instruments and greater in number than the number of said cranks, and connections from such pitmen to such stitching instruments, including rocking levers and links moving in planes perpendicular to the shaft, whereby the crank motion is transmitted to the stitching instruments to operate the same 85 in proper timing to produce successive 90 stitches.

3. A wax-thread, chain-stitch welt sewing machine for attaching together shoe upper and sole lip, the same having at least five movable stitching instruments inclusive of 100 the hooked needle, thread looper, take-up, thread hook, and feed devices for the work and welt, each mounted for its coöperative movement in relation to the others, and a harmonic actuating mechanism for said 105 stitching instruments, comprising an operating crank shaft continuously rotatable during stitching and having two differently timed cranks, four pitmen engaging and driven by said cranks, and connections from 110 such pitmen to such stitching instruments, including compactly arranged rocking levers and links, whereby the crank motion is transmitted to the stitching instruments to smoothly operate the same in proper timing 115 to produce successive stitches.

4. In a shoe sewing machine for attaching together the upper and sole lip, the combination with the curved, hooked needle and coöperating stitch-forming instruments, of 120 an operating crank shaft continuously rotatable during stitching, pitmen actuated by said crank shaft, a rock lever (70) oscillated by one of said pitmen, and a needle block connected for oscillation by said rock lever, 125 said pitman, rock lever and needle block movable in planes perpendicular to said shaft and constructed and arranged to harmonically operate the needle to take part in producing successive stitches. 130

5. In a shoe sewing machine for attaching together the upper and sole lip, the combination with the curved, hooked needle and coöperating stitch-forming instruments, of an operating crank shaft continuously rotatable during stitching, pitmen actuated by said crank shaft, a rock lever (70) oscillated by one of said pitmen through a guided link (72), and a needle block link connected 5 for oscillation by said rock lever, said pitman, rock lever, links, and needle block movable in planes perpendicular to said shaft and constructed and arranged to harmonically operate the needle to take part in producing successive stitches.
6. In a shoe sewing machine for attaching together the upper and sole lip, the combination with the curved, hooked needle, looper, and coöperating stitch-forming instruments, of an operating crank shaft continuously rotatable during stitching, pitmen actuated by said crank-shaft, a nut and screw actuator for rotating the looper, and rock arm and link connections from one 20 of said pitmen for relatively sliding the nut to operate the looper in harmony with the needle.
7. In a shoe sewing machine for attaching together the upper and sole lip, the combination with the curved, hooked needle, thread hook, and coöperating stitch-forming instruments, of an operating crank shaft continuously rotatable during stitching, pitmen actuated by said crank shaft, a rock 30 arm (81) oscillated by one pitman, a rock arm (87) oscillated by a different pitman, and a three-link connection (88, 89, 90) from said two arms to said thread hook to operate it in harmony with the needle.
8. In a shoe sewing machine for attaching together the upper and sole lip, the combination with the curved, hooked needle, welt feed and guide member, and coöperating stitch-forming instruments, of an operating 40 crank shaft continuously rotatable during stitching, pitmen actuated by said crank shaft, a rock arm (73) oscillated from one pitman, a link (103) between said rock arm and a different pitman, a link (104) therefrom, a lever 105 oscillated by said link, and connections from said lever to said member.
9. In a shoe welt sewing machine for attaching together the upper and sole lip, the combination with the curved, hooked needle, looper, thread hook, feed device, and coöperating stitch-forming instruments, of an operating crank shaft continuously rotatable during stitching, pitmen actuated by said crank shaft, a rock lever (70) oscillated 50 by one of said pitmen, a needle block connected for oscillating by said rock lever, a second rock lever (81), and a link connection to said thread hook from both said rock levers, said pitmen, levers and links movable in planes perpendicular to said shaft and constructed 60 to move in planes perpendicular to said shaft and constructed to operate the needle and thread hook to take part in producing successive stitches.
10. In a shoe welt sewing machine for attaching together the upper and sole lip, the combination with the curved, hooked needle, looper, thread hook, feed device, and coöperating stitch-forming instruments, of an operating crank shaft continuously rotatable during stitching, pitmen actuated by 70 said crank shaft, a rock lever (70) oscillated by one of said pitmen, a needle block connected for oscillating by said rock lever, a second rock lever (81), a link connection to said thread hook from both said rock levers; 80 a third rock lever (76), and connections to said feed device from said third rock lever and another of said rock levers; said pitmen, levers and links movable in planes perpendicular to said shaft and constructed 85 to operate the needle and thread hook and feed device to take part in producing successive stitches.
11. In a shoe welt sewing machine for attaching together the upper and sole lip, the combination with the curved, hooked needle, looper, thread hook, feed device, and coöperating stitch-forming instruments, of an operating crank shaft continuously rotatable during stitching, pitmen actuated by 90 said crank shaft, a rock lever (70) oscillated by one of said pitmen, a needle block connected for oscillating by said rock lever, a second rock lever (76) and connections to said feed device from both said rock levers; 95 said pitmen, levers and links movable in planes perpendicular to said shaft and constructed to operate the needle and feed device to take part in producing successive stitches.
12. In a shoe welt sewing machine for attaching together the upper and sole lip, the combination with the curved, hooked needle, looper, thread hook, feed device, and coöperating stitch-forming instruments, of an 100 operating crank shaft continuously rotatable during stitching, pitmen actuated by said crank shaft, a rock lever (81) oscillated by one of said pitmen, a second rock lever (87) oscillated by a different pitman, a link 110 connection to said thread hook from both said rock levers, and a link connection from one of said rock levers to said looper, said pitmen, levers and links movable in planes perpendicular to said shaft and constructed 115 to operate the looper and thread hook to take part in producing successive stitches.
13. In a shoe welt sewing machine for attaching together the upper and sole lip, the combination with the curved, hooked needle, 120 looper, thread hook, feed device, and coöperating stitch-forming instruments, of an operating crank shaft continuously rotatable during stitching, pitmen actuated by said crank shaft, a rock lever (81) oscillated 125 by one of said pitmen, a needle block connected for oscillating by said rock lever, a second rock lever (81), and a link connection to said thread hook from both said rock levers, said pitmen, levers and links movable in planes perpendicular to said shaft and constructed 130 to move in planes perpendicular to said shaft and constructed to operate the needle and thread hook to take part in producing successive stitches.

by one of said pitmen, a second rock lever (87) oscillated by a different pitman, a link connection to said thread hook from both said rock levers, and a link connection from 5 one of said rock levers to said looper, a third rock lever (76) oscillated from one of said other rock levers, and connections from said third rock lever for actuating said feed device, said pitmen, levers and links movable 10 in planes perpendicular to said shaft and constructed to operate the looper and thread hook and feed device to take part in producing successive stitches.

14. In a shoe sewing machine for attaching 15 together the upper and sole lip, the combination with the curved, hooked needle, looper, thread hook, feed device, and coöperating stitch-forming instruments, of an operating crank shaft continuously rotatable during stitching, pitmen actuated by 20 said crank shaft, a rock lever (70) oscillated by one of said pitmen, a second rock lever (76) concentric with said first rock lever, a third rock lever (81) oscillated from a different pitman, a link connection by which 25 the third rock lever oscillates the second rock lever, link connections from the first and third rock levers for actuating the thread hook, and connections from the first and 30 second rock levers for actuating the feed device; said pitmen, levers and links movable in planes perpendicular to said shaft and constructed to operate the looper and feed device to take part in producing successive 35 stitches.

15. A hooked-needle chain-stitch shoe sewing machine of the class for attaching together shoe upper and sole lip, the same having at least the following movable stitching 40 instruments, hooked needle, thread looper, take-up, and work feed device, each mounted for coöperative movement in relation to the others, and mechanism for actuating said stitching instruments, comprising an operating crank shaft laterally arranged behind the sewing point and continuously rotatable during stitching, a plurality of differently timed 45 pitmen crank-driven from said crank shaft, and connections from such pitmen to the stitching instruments, including rocking levers and links moving in fore-and-aft planes perpendicular to the shaft, and constructed, arranged and timed to operate in each cycle to actuate the needle with 50 a harmonic motion to advance and penetrate the work and retract with a new thread loop, and to actuate the looper to place a thread loop on the hook of the advanced needle on each stroke, and to actuate the take-up coöperatively and with a harmonic motion to 55 take up the slack thread during each advancing needle stroke and to give thread on the return stroke.

16. A hooked-needle chain-stitch shoe 60 sewing machine of the class for attaching

together shoe upper and sole lip, the same having at least the following movable stitching instruments, hooked needle, thread looper, take-up, and work feed device, each mounted for coöperative movement in relation to the others, and mechanism for actuating said stitching instruments, comprising an operating crank shaft laterally arranged behind the sewing point and continuously rotatable during stitching, the same 70 having a plurality of differently timed cranks, a plurality of pitmen crank-driven from said cranks, and connections from such pitmen to the stitching instruments, including rocking levers and links moving in fore-and-aft planes perpendicular to the shaft, and constructed, arranged and timed to operate in each cycle to actuate the needle with a harmonic motion to advance and penetrate the work and retract with a new thread loop, 75 and to actuate the looper to place a thread loop on the hook of the advanced needle on each stroke and to actuate the take-up coöperatively and with a harmonic motion to take up the slack thread during each advancing needle stroke and to give thread on the return stroke; said looper deriving its movements from one of said shaft cranks, and said needle and take-up both deriving motion from another of said cranks, through 80 differently timed pitmen.

17. A hooked-needle chain-stitch shoe sewing machine of the class for attaching together shoe upper and sole lip, the same having at least the following movable stitching instruments, hooked needle, thread looper, take-up, and work feed device, each mounted for coöperative movement in relation to the others, and mechanism for actuating said stitching instruments, comprising an operating crank shaft laterally arranged behind the sewing point and continuously rotatable during stitching, the same having a plurality of differently timed cranks, a plurality of pitmen crank-driven from said cranks, and connections from such pitmen to the stitching instruments, including rocking levers and links moving in fore-and-aft planes perpendicular to the shaft, and constructed, arranged and timed to operate in each cycle to actuate the needle with a harmonic motion to advance and penetrate the work and retract with a new thread loop, 100 and to actuate the looper to place a thread loop on the hook of the advanced needle on each stroke and to actuate the take-up coöperatively and with a harmonic motion to take up the slack thread during each advancing needle stroke and to give thread on the return stroke; an axle to the rear of and parallel to said shaft, a rocking lever included in the needle connections swinging on said axle, and a different rocking lever included in the take-up connections also 105 swinging on said axle.

18. A hooked - needle chain - stitch shoe sewing machine of the class for attaching together shoe upper and sole lip, the same having at least the following movable stitching instruments, hooked needle C, thread looper D, take-up F, and work feed device G, each mounted for coöperative movement in relation to the others, and mechanism for actuating said stitching instruments, comprising an operating crank shaft 53 laterally arranged behind the sewing point and continuously rotatable during stitching, a plurality of pitmen 61, 63, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage and advance the work while the needle is out of the work and to disengage the work and return, and to actuate coöperatively the other instruments.
19. A hooked - needle chain - stitch shoe sewing machine of the class for attaching together shoe upper and sole lip, the same having at least the following movable stitching instruments, hooked curved needle C, thread looper D, take-up F, thread hook E, channel guide B and feed device G, each mounted for coöperative movement in relation to the others, and mechanism for actuating said stitching instruments, comprising an operating crank shaft 53 laterally arranged behind the sewing point and continuously rotatable during stitching, a plurality of pitmen crank-driven from said crank shaft, and connections from such pitmen to the stitching instruments, including rocking levers and link moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage and advance the work while the needle is out of the work and to disengage the work and return, and to actuate coöperatively the other instruments; said connections including a single crank - actuated rocker 70 from which both the needle and feed device derive their motions.
20. A hooked - needle chain - stitch shoe sewing machine of the class for attaching together shoe upper and sole lip, the same having at least the following movable stitching instruments, hooked curved needle C, thread looper D, take-up F, thread hook E, channel guide B and feed device G, each mounted for coöperative movement in relation to the others, and mechanism for actuating said stitching instruments, comprising an operating crank shaft laterally arranged behind the sewing point and continuously rotatable during stitching, a plurality of differently timed pitmen crank-driven from said crank shaft, and connections from such pitmen to the stitching instruments, including rocking levers and links moving in fore-and-aft planes perpendicular to the shaft, and constructed, arranged and timed to operate in each cycle to actuate the needle with a harmonic motion to advance and penetrate the work and retract with a new thread loop, and to actuate the looper with a harmonic motion to place a thread loop on the hook of the advanced needle on each stroke, and to actuate the take-up coöperatively to take up the slack thread during each advancing needle stroke and to give thread on the return stroke.
21. A hooked - needle chain - stitch shoe sewing machine of the class for attaching together shoe upper and sole lip, the same having at least the following movable stitching instruments, hooked needle, thread looper, take-up, and work feed device, each mounted for coöperative movement in relation to the others, and mechanism for actuating said stitching instruments, comprising an operating crank shaft laterally arranged behind the sewing point and continuously rotatable during stitching, a plurality of differently timed pitmen crank-driven from said crank shaft, and connections from such pitmen to the stitching instruments, including rocking levers and links moving in fore-and-aft planes perpendicular to the shaft, and constructed, arranged and timed to operate in each cycle to actuate the needle to make its advance and return strokes with a harmonic motion to penetrate the work and retract with a new thread loop, and to actuate the feed device to engage and advance the work while the needle is out of the work and to disengage the work and return, and to actuate coöperatively the other instruments.

- structed, arranged and timed to operate in each cycle to actuate the needle with a harmonic motion to advance and penetrate the work and retract with a new thread loop, and to actuate the looper to place a thread loop on the hook of the advanced needle on each stroke, and to actuate the take-up coöperatively and with a harmonic motion to take up the slack thread during each advancing needle stroke and to give thread on the return stroke, and to actuate the feed device to engage and advance the work while the needle is cut of the work and to disengage the work and return, and coöperatively to actuate the other instruments.
23. A hooked-needle chain-stitch shoe sewing machine of the class for attaching together shoe upper and sole lip, the same having at least the following movable stitching instruments, hooked curved needle, thread looper D, take-up F, thread hook E, channel guide B and feed device G, the feed device mounted to advance and recede along the direction of feed and to reciprocate toward and from the work, and the other instruments mounted for coöperative movements, and mechanism for actuating said stitching instruments, comprising an operating crank shaft 53 continuously rotatable during stitching, a plurality of pitmen crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage the work, and then advance the work while the needle is out of the work, and then disengage the work and then recede, and to actuate coöperatively the other instruments.
24. A hooked-needle chain-stitch shoe sewing machine of the class for attaching together shoe upper and sole lip, the same having at least the following movable stitching instruments, hooked curved needle, thread looper D, take-up F, thread hook E, channel guide B, and feed device G, the feed device mounted to advance and recede along the direction of feed and to reciprocate toward and from the work, and the other instruments mounted for coöperative movements, and mechanism for actuating said stitching instruments, comprising an operating crank shaft 53 continuously rotatable during stitching, the same having a plurality of differently timed cranks, 56, 57, a plurality of pitmen crank-driven from said cranks, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage the work, and then advance the work while the needle is out of the work, and then disengage the work and then recede, and to actuate coöperatively the other instruments; the feed device connections including differently timed rockers 70, 76, coaxially arranged, each actuated by one of said cranks and the two rockers respectively connected for producing the advance and return movements and the reciprocating movements of the feed device.
25. A hooked-needle chain-stitch shoe sewing machine of the class for attaching together shoe upper and sole lip, the same having at least the following movable stitching instruments, hooked curved needle, thread looper D, take-up F, thread hook E, channel guide B and feed device G, the feed device mounted to advance and recede along the direction of feed and to reciprocate toward and from the work, and the other instruments mounted for coöperative movements, and mechanism for actuating said stitching instruments, comprising an operating crank shaft 53 continuously rotatable during stitching, the same having a plurality of differently timed cranks, 56, 57, a plurality of pitmen crank-driven from said cranks, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage the work, and then advance the work while the needle is out of the work, and then disengage the work and then recede, and to actuate coöperatively the other instruments; the feed device connections including separate trains, one deriving its motion from one shaft crank 56 for advancing and returning the feed device, and the others from another crank 57 for reciprocating the feed device.
26. A hooked-needle chain-stitch shoe sewing machine of the class for attaching together shoe upper and sole lip, the same having at least the following movable stitching instruments, hooked curved needle, thread looper D, take-up F, thread hook E, channel guide B and feed device C, the feed device mounted to advance and recede along the direction of feed and to reciprocate toward and from the work, and the other instruments mounted for coöperative movements, and mechanism for actuating said stitching instruments, comprising an oper-

- ating crank shaft 53 continuously rotatable during stitching, the same having a plurality of differently timed cranks 56, 57, a plurality of pitmen crank-driven from said 5 cranks, and connections from such pitmen to the stitching instruments, including rocking levers and links moving in planes perpendicular to the shaft, and constructed, arranged and timed to operate in each cycle 10 to actuate the needle to make its advance and return strokes with a harmonic motion to penetrate the work and retract with a new thread loop, and to actuate the feed device to engage the work, and then advance 15 the work while the needle is out of the work, and then disengage the work and then recede, and to actuate co-operatively the other instruments; the feed device connections including a bell crank contrivance 100 actuated at right angles to the shaft and operating to produce feeding and return movements in said feed device parallel to the shaft, and connections for reciprocating the feed device. 20 25 27. A hooked-needle chain-stitch shoe sewing machine of the class for attaching together shoe upper and sole lip, the same having at least the following movable stitching instruments, hooked curved needle, thread looper D, take-up F, thread hook E, channel guide B and feed device G, the feed 70 device and channel guide B both mounted to advance and recede along the direction of feed and to reciprocate toward and from the work, and the other instruments mounted for co-operative movements, and mechanism for actuating said stitching instruments, comprising an operating crank shaft 53 continuously rotatable during stitching, a plurality of pitmen crank-driven from 75 said crank shaft, and connections from such pitmen to the stitching instruments, including rocking levers and links moving in planes perpendicular to the shaft, and constructed, arranged and timed to operate in each cycle to actuate the needle to make 80 its advance and return strokes with a harmonic motion to penetrate the work and retract with a new thread loop, and to actuate the feed device to engage the work, and then advance the work while the needle is out of 85 the work, and then disengage the work and then recede, and to actuate co-operatively the channel guide and other instruments. 90 30 35 40 45 50 55 60 65 70 75 80 85 90 95 100 105 110 115 120 125 130 29. A hooked-needle chain-stitch shoe sewing machine of the class for attaching together shoe upper and sole lip, the same having at least the following movable stitching instruments, hooked curved needle C, thread looper D, take-up F, thread hook E, channel guide B and feed device G, each 100 mounted for co-operative movement in relation to the others, and mechanism for actuating said stitching instruments, comprising an operating crank shaft 53 continuously rotatable during stitching, a plurality of pitmen 61, 63, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the looper to place a thread loop on the hook of the advanced needle on each stroke, and to actuate the thread hook with a harmonic motion to take the thread between the looper and work and release the same after the loop is safely 120 on the needle hook. 30. A hooked-needle chain-stitch shoe sewing machine of the class for attaching together shoe upper and sole lip, the same having at least the following movable stitching instruments, hooked curved needle C, thread looper D, take-up F, thread hook E, channel guide B and feed device G, each 125 mounted for co-operative movement in relation to the others, and mechanism for actu-
- ating crank shaft 53 continuously rotatable during stitching, the same having a plurality of differently timed cranks 56, 57, a plurality of pitmen crank-driven from said cranks, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage the work, and then advance the work while the needle is out of the work, and then disengage the work and then recede, and to actuate co-operatively the other instruments; the feed device connections including a bell crank contrivance 100 actuated at right angles to the shaft and operating to produce feeding and return movements in said feed device parallel to the shaft, and connections for reciprocating the feed device.
27. A hooked-needle chain-stitch shoe sewing machine of the class for attaching together shoe upper and sole lip, the same having at least the following movable stitching instruments, hooked curved needle, thread looper D, take-up F, thread hook E, channel guide B and feed device G, the feed device and channel guide B both mounted to advance and recede along the direction of feed and to reciprocate toward and from the work, and the other instruments mounted for co-operative movements, and mechanism for actuating said stitching instruments, comprising an operating crank shaft 53 continuously rotatable during stitching, a plurality of pitmen crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the feed device to engage the work, and then advance the work while the needle is out of the work, and then disengage the work and then recede, and to actuate co-operatively the channel guide and other instruments.
29. A hooked-needle chain-stitch shoe sewing machine of the class for attaching together shoe upper and sole lip, the same having at least the following movable stitching instruments, hooked curved needle C, thread looper D, take-up F, thread hook E, channel guide B and feed device G, each mounted for co-operative movement in relation to the others, and mechanism for actuating said stitching instruments, comprising an operating crank shaft 53 continuously rotatable during stitching, a plurality of pitmen 61, 63, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the looper to place a thread loop on the hook of the advanced needle on each stroke, and to actuate the thread hook with a harmonic motion to take the thread between the looper and work and release the same after the loop is safely on the needle hook.
30. A hooked-needle chain-stitch shoe sewing machine of the class for attaching together shoe upper and sole lip, the same having at least the following movable stitching instruments, hooked curved needle C, thread looper D, take-up F, thread hook E, channel guide B and feed device G, each mounted for co-operative movement in relation to the others, and mechanism for actu-

ating said stitching instruments, comprising an operating crank shaft 53 continuously rotatable during stitching, a plurality of pitmen 61, 63, etc., crank-driven from said 5 crank shaft, and connections from such pitmen to the stitching instruments, including rocking levers and links moving in planes perpendicular to the shaft, and constructed, arranged and timed to operate in each cycle 10 to actuate the needle to make its advance and return strokes with a harmonic motion to penetrate the work and retract with a new thread loop, and to actuate the looper to place a thread loop on the hook of the advanced needle on each stroke, and to actuate the thread hook with a harmonic motion 15 to take the thread between the looper and work and release the same after the loop is safely on the needle hook, the needle and 20 thread hook connections comprising a rocker 70 driven by one pitman 63, a second rocker 81 driven by another pitman 61, link connections from both said rockers to the thread hook, and a connection from said 25 rocker 70 to the needle.

31. A hooked-needle chain-stitch shoe sewing machine of the class for attaching together shoe upper and sole lip, the same having at least the following movable 30 stitching instruments, hooked curved needle C, thread looper D, take-up F, thread hook E, channel guide B and feed device G, each mounted for co-operative movement in relation to the others, and mechanism for actuating said stitching instruments, comprising an operating crank shaft 53 continuously rotatable during stitching, a plurality of pitmen 61, 63, etc., crank-driven from said 35 crank shaft, and connections from such pitmen to the stitching instruments, including rocking levers and links, moving in planes perpendicular to the shaft, and constructed, arranged and timed to operate in each cycle 40 to actuate the needle to make its advance and return strokes with a harmonic motion to penetrate the work and retract with a new thread loop, and to actuate the looper to place a thread loop on the hook of the advanced needle on each stroke, and to actuate 45 the thread hook with a harmonic motion to take the thread between the looper and work and release the same after the loop is safely on the needle hook, the needle, looper and thread hook connections comprising a rocker 70 driven by one pitman 63, a second rocker 81 driven by another pitman 61, link connections from both said rockers to the thread hook, connections from rocker 50 55 60 65 70 to the looper, and a connection from said rocker 70 to the needle.

32. A hooked-needle chain-stitch shoe sewing machine of the class for attaching together shoe upper and sole lip, the same having at least the following movable stitching instruments, hooked curved needle C,

thread looper D, take-up F, thread hook E, channel guide B and feed device G, each mounted for co-operative movement in relation to the others, and mechanism for actuating said stitching instruments, comprising an operating crank shaft 53 continuously rotatable during stitching, a plurality of pitmen 61, 63, etc., crank-driven from said crank shaft, and connections from such pitmen to the stitching instruments, 70 including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the looper to place a thread loop on the hook of the advanced needle on each stroke, and to actuate the thread hook with a harmonic motion to take the thread between the looper and work and release the same after the loop is safely on the needle hook, the looper and thread hook connections comprising a rocker 70 driven by one pitman 63, a second rocker 81 driven by another pitman 61, link connections from both said rockers to the thread hook, connections from rocker 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470

33. A hooked-needle chain-stitch shoe sewing machine of the class for attaching together shoe upper and sole lip, the same having at least the following movable stitching instruments, hooked curved needle C, thread looper D, take-up F, thread hook E, channel guide B and feed device G, each mounted for co-operative movement in relation to the others, and mechanism for actuating said stitching instruments, comprising an operating crank shaft 53 continuously rotatable during stitching, a plurality of pitmen 61, 63, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the looper with a harmonic motion to place a thread loop on the hook of the advanced needle on each stroke, and to actuate the thread hook with a harmonic motion to take the thread between the looper and work and release the same after the loop is safely on the needle hook, and to actuate the take-up with a harmonic motion to take up the slack thread during each advancing needle stroke and to give thread on the return stroke.

34. A hooked-needle chain-stitch shoe welt sewing machine of the class for attaching together the welt, upper and sole lip, the same having at least the following movable

stitching instruments, hooked curved needle C, thread looper D, take-up F, thread hook E, channel guide B, work feed device G, and welt guide H, each mounted for coöperative movement in relation to the others, and mechanism for actuating said stitching instruments, comprising an operating crank shaft 53 continuously rotatable during stitching, a plurality of pitmen 63, 65, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the welt guide to measure off welt while the needle is in the work and to lay the measured welt against the work during the feed of the work, and to actuate coöperatively the other instruments.

35. A hooked-needle chain-stitch shoe welt sewing machine of the class for attaching together the welt, upper and sole lip, the same having at least the following movable stitching instruments, hooked curved needle C, thread looper D, take-up F, thread hook E, channel guide B, work feed device G, and welt guide H, each mounted for coöperative movement in relation to the others, and mechanism for actuating said stitching instruments, comprising an operating crank shaft 53 continuously rotatable during stitching, a plurality of pitmen 63, 65, etc., crank-driven from said crank shaft, and connections from such pitmen to the stitching instruments, including rocking levers and links moving in planes perpendicular to the shaft, and constructed, arranged and timed to operate in each cycle to actuate the needle to make its advance and return strokes with a harmonic motion to penetrate the work and retract with a new thread loop, and to actuate the welt guide to measure off welt while the needle is in the work and to lay the measured welt against the work during the feed of the work, and to actuate coöperatively the other instruments, such needle and welt guide connections comprising a rocker 70 driven from pitman 63, connections from said rocker to the needle, and connections jointly from said rocker and pitman 65 to the welt guide.

36. A hooked-needle chain-stitch shoe sewing machine of the class for attaching together shoe upper and sole lip, the same having at least the following movable stitching instruments, hooked curved needle C, thread looper D, take-up F, and work feed device G, each mounted for coöperative movement in relation to the others, and mechanism for actuating said stitching instruments, comprising an operating crank shaft 53 having differently timed cranks 56, 57, a rocker 70, a pitman 63 on crank 57 for oscillating said rocker, a link connection from said rocker for actuating the needle with a harmonic motion to advance and penetrate the work and retract with a

shaft 53 having differently timed cranks 56, 57, said shaft arranged laterally behind the sewing point and continuously rotatable during stitching, in combination with differently timed crank driven pitmen 61, 63, 64, 65, fewer in number than the number of stitching instruments actuated therefrom, and connections from such pitmen to the stitching instruments, including rocking levers and links moving in fore - and - aft planes perpendicular to the shaft, said pitmen, rocking levers and links being arranged in compact transverse juxtaposition, and constructed, arranged and timed to operate in each cycle to actuate the hooked needle with a harmonic motion to advance and penetrate the work and retract with a thread loop, and to actuate the take-up with a coöperating motion to take up the slack thread during each advancing needle stroke and to give thread on the return stroke, and to actuate coöperatively the other enumerated instruments.

37. A hooked-needle chain-stitch shoe sewing machine of the class for attaching together shoe upper and sole lip, the same having at least the following movable stitching instruments, hooked curved needle C, thread looper D, take-up F, and work feed device G, each mounted for coöperative movement in relation to the others, and mechanism for actuating said stitching instruments, comprising an operating crank shaft 53 having differently timed cranks, said shaft arranged laterally behind the sewing point and continuously rotatable during stitching, in combination with differently timed crank driven pitmen 61, 63, 64, 65, fewer in number than the number of stitching instruments actuated therefrom, and connections from such pitmen to the stitching instruments, including rockers 70, 81, and connecting links moving in fore-and-aft planes perpendicular to the shaft, constructed, arranged and timed to operate in each cycle to actuate the hooked needle with a harmonic motion to advance and penetrate the work and retract with a thread loop, and to actuate coöperatively others of said instruments.

38. A hooked-needle chain-stitch shoe sewing machine of the class for attaching together shoe upper and sole lip, the same having at least the following movable stitching instruments, hooked curved needle C, thread looper D, take-up F, and work feed device G, each mounted for coöperative movement in relation to the others, and mechanism for actuating said stitching instruments, comprising an operating crank shaft 53 having differently timed cranks 56, 57, a rocker 70, a pitman 63 on crank 57 for oscillating said rocker, a link connection from said rocker for actuating the needle with a harmonic motion to advance and penetrate the work and retract with a

- thread loop, other pitmen on said cranks, and connections from said rocker 70 and said other pitmen for actuating the other instruments coöperatively with said needle.
- 5 39. A hooked-needle chain-stitch shoe sewing machine of the class for attaching together shoe upper and sole lip, the same having at least the following movable stitching instruments, hooked curved needle C, 70
10 thread looper D, thread hook E, channel guide B, and work feed device G, each mounted for coöperative movement in relation to the others, and mechanism for actuating said stitching instruments, comprising an operating crank shaft 53 having differently timed cranks 56, 57, a pitman 61 on said crank 56, a rocker 81 actuated by said pitman 61, a pitman 63 on said crank 57, a rocker 70 actuated by said pitman 63, 75
15 and link and rock lever connections from said two rockers for actuating said enumerated instruments with harmonic motions, said pitmen, rockers, links and levers being arranged in compact transverse juxtaposition and movable in planes perpendicular to the shaft.
- 20 40. A hooked-needle chain-stitch shoe sewing machine of the class for attaching together shoe upper and sole lip, the same having at least the following movable 80
25 stitching instruments, hooked curved needle C, thread looper D, thread hook E, take-up F, and work feed device G, each mounted for coöperative movement in relation to the others, and harmonic actuating mechanism 85
30 for said stitching instruments, comprising an operating crank shaft 53 having differently timed cranks, and continuously rotatable during stitching, in combination 90
35 with differently timed crank driven pitmen 61, 63, 64, 65, rocking members 70, 81, 91, driven from said pitmen, and links actuated by said rocking members for operating all 95
40 of said stitching instruments C, D, E, F, G, 45 said pitmen, rocking levers and links moving in planes perpendicular to the shaft, and constructed, arranged and timed to transmit the crank motion to the several instruments to produce successive stitches.
- 50 41. A hooked-needle chain-stitch shoe sewing machine of the class for attaching together shoe upper and sole lip, the same having at least the following movable 100
55 stitching instruments, hooked curved needle C, thread looper D, thread hook E, take-up F, and work feed device G, each mounted for coöperative movement in relation to the others, and harmonic actuating mechanism 105
60 for said stitching instruments, comprising an operating crank shaft 53 having differently timed cranks, including a crank 56, and a crank 57 between 45° and 90° in advance of crank 56, a pitman 63 on said crank 57, a rocker 70 oscillated through said 110
65 pitman, other pitmen on said cranks, and link and rock-lever connections from said rocker 70 and said other pitmen for coöperatively actuating said stitching instruments in harmony to produce successive 115
70 stitches.
42. A hooked-needle chain-stitch shoe sewing machine of the class for attaching together shoe upper and sole lip, the same having at least the following movable stitching instruments, hooked curved needle C, 75
75 thread looper D, take-up F, and work feed device G, each mounted for coöperative movement in relation to the others, and mechanism for actuating said stitching instruments, comprising an operating crank 80
80 shaft 53 having differently timed cranks and continuously rotatable during stitching, a plurality of differently timed pitmen actuated by said shaft cranks, a rocker 70 oscillated by one of said pitmen, a needle 85
85 block c connected for oscillation by said rocker, whereby the needle with a harmonic motion advances, penetrates the work, and retracts with a thread loop, and connections including links and rock levers actuated from said pitmen for coöperatively actuating others of said stitching instruments, said pitmen, rocker, needle block, links and rock levers being mounted to move in planes perpendicular to said shaft.
43. A hooked-needle chain-stitch shoe sewing machine of the class for attaching together shoe upper and sole lip, the same having at least the following movable stitching instruments, hooked curved needle C, 90
95 thread looper D, take-up F, and work feed device G, each mounted for coöperative movement in relation to the others, a swinging needle block c carrying said needle, and mechanism for actuating said stitching instruments, comprising an operating crank 100
100 shaft 53 having differently timed cranks, said shaft arranged laterally behind the sewing point and continuously rotatable 105
105 during stitching, in combination with a pitman 63 driven by one of said cranks, a guided link 72 pivoted to said pitman, a rocking lever 73 fulcrumed behind the shaft and extending forwardly and oscillated by said link, a link 80 connecting said lever to 110
110 said swinging needle block c, the said train of parts moving in planes perpendicular to said shaft and acting to operate the needle with harmonic motions.
44. A hooked-needle chain-stitch shoe sewing machine of the class for attaching together shoe upper and sole lip, the same having at least the following movable stitching instruments, hooked curved needle C, 115
120 thread looper D, take-up F, and work feed device G, each mounted for coöperative movement in relation to the others, and mechanism for actuating said stitching instruments, comprising an operating crank 125
125 shaft 53 having differently timed cranks, 130

5 said shaft arranged laterally behind the sewing point and continuously rotatable during stitching, in combination with a pitman 61
 10 driven by one of said cranks, a rocking lever 81 having its forward end fulcrumed forward of said shaft and its rear end swung by said pitman, a second rocking lever 83 having its rear end pivoted above said lever 81, a link 82 connecting intermediate points 15 on said levers 81, 83, and a screw actuator for said looper actuated from the forward end of said lever 83, the said train of parts moving in planes perpendicular to said shaft and acting to operate the looper with
 20 harmonic motions.

45. A hooked-needle chain-stitch shoe sewing machine of the class for attaching together shoe upper and sole lip, the same having at least the following movable stitching instruments, hooked curved needle C, thread looper D, take-up F, and work feed device G, each mounted for coöperative movement in relation to the others, and mechanism for actuating said stitching instruments, comprising an operating crank shaft 53 having differently timed cranks, said shaft arranged laterally behind the sewing point and continuously rotatable during stitching, in combination with a rocker 25 50 driven from one crank and having connections for actuating the needle, a rocker 81 driven from a different crank and having connections for actuating the looper, links 88 and 89 pivoted to each other and 55 60 pivoted respectively to said two rockers, and a link 90 actuated through said two links 65 for actuating the thread hook, the said train

of parts moving in planes perpendicular to said shaft and acting to operate the thread hook with harmonic motions. 40

46. A hooked-needle chain-stitch shoe sewing machine of the class for attaching together shoe upper and sole lip, the same having at least the following movable stitching instruments, hooked curved needle C, 45 thread looper D, take-up F, and work feed device G, each mounted for coöperative movement in relation to the others, and mechanism for actuating said stitching instruments, comprising an operating crank shaft 53 having differently timed cranks, said shaft arranged laterally behind the sewing point and continuously rotatable during stitching, in combination with pitmen 63 and 64, both crank driven from said 50 shaft but in different time, a rock lever 70 driven by pitman 63, a rock lever 91 driven by pitman 64, both said rock levers fulcrumed to the rear of said shaft and extending forwardly, and link connections respectively from said rock levers to said needle and take-up, the said trains of parts moving in planes perpendicular to said shaft and acting to operate the needle and take-up coöperatively and with harmonic motions. 55 60

In testimony whereof, we have affixed our signatures in presence of two witnesses.

FRANK ZALESKI.
 AUGUST R. SCHOENKY.

Witnesses:

DONALD CAMPBELL,
 F. A. SHEA.

It is hereby certified that in Letters Patent No. 1,288,366, granted December 17, 1918, upon the application of Frank Zaleski, of Cambridge, and August R. Schoenky, of Somerville, Massachusetts, for an improvement in "Machines for Stitching Shoe-Uppers to Sole-Lips," errors appear in the printed specification requiring correction as follows: Page 7, lines 52, 69, 89, 106, 123, claims 9, 10, 11, 12, 13, strike out the word "welt"; page 10, line 124, claim 26, for the reference-letter "C" read *G*; and that the said Letters Patent should be read with these corrections therein that the same may conform to the record of the case in the Patent Office.

Signed and sealed this 28th day of January, A. D., 1919.

[SEAL.]

R. F. WHITEHEAD,
Acting Commissioner of Patents.

Cl. 112—20.
